J. D. S. HASLETT.
GUN RECOIL MECHANISM.
APPLICATION FILED APR. 9, 1915.

1,147,941.

Patented July 27, 1915.

Inventor:

John D. S. Haslett,

By Charles H. Butler

Attorney

UNITED STATES PATENT OFFICE.

JOHN D. S. HASLETT, OF PHILADELPHIA, PENNSYLVANIA.

GUN RECOIL MECHANISM.

1,147,941.

Specification of Letters Patent.

Patented July 27, 1915.

Application filed April 9, 1915. Serial No. 20,147.

To all whom it may concern:

Be it known that I, JOHN D. S. HASLETT, a citizen of the United States, residing in the city of Philadelphia, county of Philadelphia, and State of Pennsylvania, have invented Improved Gun Recoil Mechanism, of which the following is a specification.

My invention relates to recoil mechanism for rifles, shot guns and fire arms of analogous character, and my leading object is to provide an improved shock absorbing mechanism of simple and efficient character that can be applied readily to the butt of a gun stock, that can be adjusted readily to take up the force of the recoil without shock, that will resist rough usage without disturbance of the correct relation of the parts or the inherent true action of the mechanism, and that can be applied and detached readily. The characteristic features of my improvements are fully disclosed in the following description and the accompanying drawings in illustration thereof.

In the drawings, Figure 1 is a broken part sectional elevation of a gun stock having my improvements applied thereto; Fig. 2 is a plan view of a detached recoil mechanism analogous to that shown in Fig. 1, and Fig. 3 is a part sectional side elevation of the same.

As shown in the drawings, the gun stock 1 has the parallel cylindrical recesses 2 formed in the butt thereof. A shoulder plate or cap 3 is provided with the flange 4, which is telescoped on the butt of the stock and is adapted to reciprocate thereon. The plate 3 is provided with the parallel cylindrical bosses and plungers 5, on which are telescoped the cylinders or casings 6, which fit in the recesses or sockets 2, the casings being provided with the interior flanges or bearings 7 adjacent to their ends beyond the plungers 5. Coiled springs 8 are disposed in the casings between the plungers 5 and the bearings 7, and the screws or bolts 9 pass through the bearings 7 and the coils of the springs 8 into the threaded sockets 10 of the plungers 5, the screws having heads engaging the flanges and being adjustable by turning them to vary the tension of the springs 8 and the consequent degree of resiliency of the recoil mechanism. A plate 11 is provided with the apertures 12 through which the plungers 5

pass freely and with the aperture 13 for a screw 14 by which the plate is fixed to the butt of the stock, which it fits. The plate 3 is provided with an aperture 15 in line with the aperture 13, for the passage of the screw 14, the aperture 15 being normally closed by a stub screw 16.

It will be understood that this mechanism is readily applied to the butt of a gun stock, provided with the sockets 2, by slipping the casings 6 into the sockets and fixing the plate 11 to the butt. The mechanism will be held with the parts in their true relation and will act correctly because the well supported casings 6, the bearings 7, the screws 9 and the plate 11 keep the plungers 5 in correct alignment. The simplicity of the construction and the readiness with which it can be attached and detached provide for ready access to the screws 9 and the ready adjustment of the mechanism to the force of the recoil.

Having described my invention, I claim:

1. The combination with a gun stock having substantially parallel tubular casings set in the butt thereof, said casings having bearings therein, of a plate having pistons thereon adapted to reciprocate in said casings, coiled springs in said casings between said bearings and plungers, screws extending through said bearings and the coils of said springs into said plungers, and a plate yoked on said plungers and fixed to the butt of said stock.

2. The combination with a gun stock, of parallel cylinders set in the butt thereof, said cylinders having internal bearing flanges, a shoulder plate having a flange thereon conforming to and adapted to reciprocate on said stock, plungers fixed to said plate and adapted to reciprocate in said cylinders, coiled springs in said cylinders adapted to bear against said flanges and pistons, bolts extending through said flanges and the coils of said springs to connections with said pistons, said bolts having parts thereon adapted to engage said flanges and to be adjustable relatively to said pistons, and a plate yoked on said plungers and fixed to the butt of said stock.

In testimony whereof I have hereunto set my name this 6th day of April, 1915.

JOHN D. S. HASLETT.
